(57) **CLAIM**

I claim, the ornamental design for the compartmented plastic packaging, as shown and described.

DESCRIPTION

FIG. 1 is a front elevational view of the compartmented plastic packaging showing my new design;

FIG. 2 is a rear elevational view thereof;

FIG. 3 is a left side elevational view thereof; and,

FIG. 4 is a top plan elevational view thereof.

The dashed lines shown in the drawing disclosure are meant to represent perforations.
